UNITED STATES PATENT OFFICE.

FREDERICK HERSCHEMANN, OF NEW YORK, N. Y.

COLLAPSIBLE TUBE.

Application filed May 27, 1924. Serial No. 716,186.

To all whom it may concern:

Be it known that I, FREDERICK HERSCHEMANN, a citizen of the United States, and a resident of the city of New York, borough 5 of Manhattan, in the county and State of New York, have invented a new and Improved Collapsible Tube, of which the following is a full, clear, and exact description.

10 This invention relates to collapsible tubes and more particularly to devices of this character which are adapted for dispensing icing for cakes and allow the same to be directed in any desired shape or form.

15 Of course, the invention is not limited to the contents of the tube as I may employ the tube for containing any liquid or semi-liquid of paste-like composition.

An object of the invention is to provide a 20 collapsible dispensing tube having a window or windows which permit observation of the contents of the tube.

A further object is to provide an improved construction and arrangement of 25 nozzle and mounting therefor which permits the outlet to be opened or closed and which directs the discharge of the contents of the tube.

30 A further object is to provide a tube of the character stated embodying novel details of construction which will facilitate the assemblage and the operation of the tube in dispensing its contents.

With these and other objects in view, the 35 invention consists in certain novel features of construction and combinations and arrangement of parts which will be more fully hereinafter described and pointed out in the claims.

40 In the accompanying drawings—

Figure 1 is a perspective view of a tube illustrating one embodiment of my invention;

45 Figure 2 is a view in longitudinal section through the center of the tube illustrated in Figure 1, the view being taken at right angles to said Figure 1;

Figure 3 is a view in section on the line 3—3 of Figure 2;

50 Figure 4 is a fragmentary view in longitudinal section showing the lower ends of the tube and lining before bending;

55 Figure 5 is a perspective view of my improved key, showing the same in its position before engagement with the tube.

Figure 6 is a perspective view illustrating a modified form of nozzle;

Figure 7 is a view in front elevation of the tube illustrating a modification;

Figure 8 is a view in transverse section 60 on the line 8—8 of Figure 7;

Figure 9 is a perspective view showing the window removed;

Figure 10 is a perspective view of the frame for holding the window in place. 65

Referring more particularly to Figures 1 to 5, inclusive, 1 represents an outer tube and 2 an inner lining. This lining 2 is also of tubular form and both the lining 2 and the tube 1 are made with registering openings 3, and flexible and bendable transparent material 4 is interposed between the tube 1 and the lining 2 and extends across the openings 3 so as to provide windows in the tube through which the contents of the tube 75 can be observed.

I have illustrated the device as provided with two of these windows at opposite sides of the tube, but it is obvious that the invention is not limited to any particular number 80 of such windows nor to their size, shape and location.

The upper end of the tube 1 is formed with a neck 5 of a reduced diameter as regards the main body of the tube 1, and this neck 5 has a closed upper end 6 provided with an eye 7 or other suitable arrangement by which the tube may be readily suspended from a hook or nail when not desired for use. 90

The upper end of the lining 2 is also formed with a restricted neck portion 8' which projects into the neck 5 of tube 1. The neck 5 is externally screw-threaded, as shown at 8 to mesh with internal screw threads in a sleeve 9. This sleeve 9 supports a discharge nozzle 10, the latter being of any desired shape in cross section but preferably provided with a screw-threaded inner end 11 to engage a threaded opening 12 in the sleeve 9 so that various nozzles can be coupled to the sleeve in accordance with the shape desired to be imparted to the contents of the tube when discharged therefrom. 100

It will be noted that the head 6 is enlarged and of greater diameter than the neck 5. This absolutely prevents accidental removal and loss of the sleeve 9. In constructing the device, the neck 5 is of the same diam- 110

eter throughout until the sleeve is positioned thereon, when the upper end of the neck can be hammered, molded or otherwise formed to give the necessary enlargement thereto.

I have illustrated in Figures 1, 2 and 3 nozzles 10 having rectangular bores, and in Figure 6 I have illustrated a nozzle 13 having a narrow somewhat elliptical shape, but 10 it is obvious that nozzles of any shape may be employed.

A discharge opening 14 is provided in the wall of the neck 5 which is adapted to register with the nozzle 10 and may be cut off when 15 the sleeve 9 is turned on the screw-threaded neck 5 so as to move the nozzle out of register with said opening. It will thus be seen that the outlet can be effectually shut off whenever desired and can be opened by 20 properly positioning the sleeve 9 to register the opening 14 with the nozzle 10.

The lower end of the lining 2 is formed with a laterally projecting tongue 15 having a head 16 at its outer end, and this tongue 25 and head project through the wall of the tube 1 and the lower end of the tube 1 extends below the lower end of the lining. The lining and the tube are open when filling the tube with its contents, after which 30 the lower end of the tube is flattened, folded on itself, the lining or, at least, one portion of the lining being bent into said fold, and then a key 17 is clamped onto the folded end of the tube and the lining.

35 This key 17, shown in perspective in Figure 5, comprises a pair of members precisely alike in shape but integrally connected and having spurs 18 projected inwardly therefrom so that when these members of the key 40 are forced against the folded lower end of the tube they will effectually clamp and hold the tube in closed formation.

The extremities of these key members conform in shape to the tongue 15 and head 16 45 of the lining 2 so that when they are in position they constitute a handle 19 projecting laterally from the tube so as to facilitate the turning of the key to wind the tube thereon and eject the contents of the tube through 50 the nozzle 10.

In the modification illustrated in Figures 7, 8, 9 and 10, I show a tube 20 corresponding to the tube 1, and instead of forming the windows 4, as shown in Figures 1 and 2, I

simply provide a single thickness of tube 20 55 with an opening or openings 21 in the wall thereof, and cover said opening or openings with sheets of transparent, flexible, bendable material 22 secured against the outer face of the tube by flexible bendable frames 23. 60 In this modification I have illustrated a bail 24 located through an eye 25 at the top of the neck portion 5 of the tube as a supporting means, but various other means may be provided for hanging or suspending the 65 device.

While I have illustrated what I believe to be the preferred embodiment of my invention, it is obvious that various slight changes and alterations might be made in the general 70 form of the parts described without departing from my invention, and hence I do not limit myself to the precise details set forth but consider myself at liberty to make such slight changes and alterations as fairly fall 75 within the spirit and scope of the appended claims.

I claim:

1. As a new article of manufacture, a collapsible dispensing tube, comprising a pair 80 of tubes, one located within the other and having registering openings, and a transparent sheet located between the tubes and across the openings and constituting a transparent window through which the contents 85 of the dispensing tube can be viewed.

2. As a new article of manufacture, a collapsible dispensing tube having a lining therein, said lining and said tube having registering openings and flexible transparent 90 material located between the tube and its lining and constituting a window whereby the contents of the tube can be seen from the outside.

3. As a new article of manufacture, a collapsible dispensing tube having a neck at one end, said neck having an opening in its wall, a sleeve movable on said neck and having an opening adapted to register with the opening in the neck or moved to a position to close said opening, a nozzle removably secured in the opening of the sleeve and constituting a form or die to shape the material expressed from the tube, means on the end of the neck for supporting the tube, 100 and a key secured to the end of the tube for collapsing the same.

FREDERICK HERSCHEIMANN.
